UNITED STATES PATENT OFFICE.

CHARLES W. WEISS, OF BROOKLYN, ASSIGNOR OF ONE-HALF TO CHARLES KRUSE, OF NEW YORK, N. Y.

ATMOSPHERIC ENGINE.

SPECIFICATION forming part of Letters Patent No. 351,081, dated October 19, 1886.

Application filed July 3, 1886. Serial No. 207,073. (No model.)

To all whom it may concern:

Be it known that I, CHARLES W. WEISS, of Brooklyn, in the county of Kings and State of New York, have invented certain new and useful Improvements in Atmospheric Engines; and I do hereby declare that the following is a full and exact description thereof, reference being had to the accompanying drawings, and to the letters of reference marked thereon, making a part of this specification, in which—

Figure 1 is a side elevation of my improved atmospheric engine; Fig. 2, a central diametric section through the cylinder and base thereof.

This invention relates to that class of engines in which the piston is driven in one direction by atmospheric pressure, the pressure on the opposite side of the piston being reduced below that of the atmosphere by the condensation of a charge of highly-rarefied air admitted thereto.

It has for its object to obtain a greater amount of work in an engine of given dimensions with a less consumption of fuel by supplying thereto a working-charge of rarefied air and gases at a much higher temperature than in the engines of this class heretofore constructed, and in more quickly condensing and discharging the same; and it consists in so constructing the engine, in manner as hereinafter described, as that the intensely-hot flame and products of combustion from a suitable burner shall be drawn directly into a hot-air chamber, be displaced from said hot-air-chamber, and delivered into a separate condensing-chamber for effective work without cooling the hot-air chamber, and, finally, after effecting by its condensation a movement of the working-piston under atmospheric pressure, be discharged from the machine.

My improved atmospheric engine is constructed of a hot-air cylinder, A, (see Fig. 1,) closed at its outer end by a suitable head-plate, b, in which is formed a narrow elongated flame-opening, C. The opposite end of the cylinder

A is left open and provided with an exterior flange, a, by means whereof it is bolted to the open end of a separate condensing-cylinder, D, of the same internal diameter, and which is provided with a counterpart exterior flange, 50 a', to receive the connecting-bolts.

The hot-air cylinder may be formed of sheet metal, but the condensing-cylinder D is preferably made of cast-iron. The outer end of the condensing-cylinder D is closed by a solid head, E, preferably recessed on its outer face 55 to receive and protect a valve, F, which, playing upon a piston-rod, G, carried through an enlarged central opening or port in the head, serves to close said port. The valve is held against the port to close it by means of a spring, 60 c. An extended piston, B, (see Fig. 2,) of a diameter somewhat smaller than that of the inner periphery of the connected cylinders A and D, is attached to the piston-rod G, and is guided and centered in the cylinder D by means 65 of an annular offset, d, formed on the internal periphery of this condensing-cylinder near to its inner end, said offset being made to embrace the piston closely, and thereby serve as a partition in the concentric space around it, 7c to cut off communication between the hot-air chamber e of the one cylinder, A, and the condensing-chamber f of the other cylinder, D. The piston B is made hollow, and is hermetically closed at both ends. Its inner end, playing in the hot-air chamber e, and against which the flame and hot-air admitted from the opening C strikes, is outwardly lined with a layer, g, of asbestos or other non-conducting material. The outer end of the piston-rod G works 75 in a bearing in a bracket or pedestal, H, which may be made fast to the head E of the cylinder D, as shown in the drawings, or otherwise properly supported. It is coupled in the customary manner to the crank I on the end of 80 the crank-shaft J of the engine by means of a connecting-rod, K, pivoted thereto, the crank-shaft being supported in bearings upon a double bracket or pedestal, H', likewise made fast to the cylinder D, or otherwise supported in 85 connection therewith. This shaft carries the driving-pulley, and also a fly-wheel, to cause it to rotate with a uniform speed, as is customary in engines of this class.

The outer end of the condensing-cylinder D 95 is surrounded by a water-jacket, D', within which a circulation is maintained by means of circulating-pipes D² D², connecting it with a water-tank, D³, or with a pump or other suitable water-supply.

- Annular grooves *i i'* are formed in the inner wall of the cylinder D, on each side of the offset *d*, and ports *j j* are pierced through the side of the cylinder in line with each other to communicate severally with said grooves. A slide-valve, L, is fitted to cover these two ports, and so constructed as to establish communication between them, and consequently between the hot-air and condensing chambers in one position thereof, and to cut off the communication in the next position. This slide-valve is actuated at the proper moment in the work of the engine by means of an eccentric, M, on the main shaft, and a coupling-rod, N.
- 15 The two cylinders A and D are insulated from each other by an interposed packing-ring, *m*, of asbestos or its equivalent, to prevent a conduction of heat from the hot-air cylinder A to the condensing-cylinder D.
- 20 The narrow extended flame opening C, in the outer end of the hot-air cylinder A, is governed by a slide-valve, O, mounted in suitable ways to traverse said opening, and which is operated to open and close the same at the proper moment by means of a bell-crank, P, pivoted to the pedestal of the main shaft, and whose longer arm is extended into line with the slide-valve, and coupled thereto by a link, P', and whose shorter arm is coupled to an eccentric, Q, on the main shaft by a rod, Q', pivoted to said short arm with a loose joint.
- 25 Immediately below or in front of the flame opening or port C in the outer end of the hot-air cylinder A a lamp, R, or a suitable burner of any description, is placed in such position as that the flame and products of combustion therefrom will be drawn directly into the port C whenever it is opened. Where a lamp, R, is employed, the flame is regulated automatically by means of a toothed wheel or segment, S, engaging the wick, and which is partially rotated in either direction by means of a radial arm, S', coupled by a link, S'', to one arm of a bell-crank, S³, whose other arm is actuated by means of a governor, S⁴, of any suitable construction, attached to the main shaft J.
- 30 In the operation of the machine thus simply constructed, as the piston B moves outwardly the hot flame from the burner R' is drawn into the cylinder A, so that the hot-air chamber *e* becomes filled with highly rarefied air and gases. As the piston moves outwardly, the slide-valve O closes, the adjustment of the several parts of the engine being so regulated as that the hot flame is drawn into the cylinder while the piston-crank is moving through about three quarters of the first half of its revolution. At this point the valve O closes, completely shutting off the inflow of hot air.
- 35 During the next quarter-turn of the crank the piston still continues to move in the same outward direction, so that the rarefied air and gases inclosed in the hot-air cylinder are thereby allowed and caused to expand more fully.
- 40 As the piston approaches the extreme end of its outward stroke, the valve L, controlling the ports *j j*, begins to open to allow a free passage

for the hot air by way of said ports from the chamber *e* into the condensing-chamber *f*. This valve L remains open while the crank is completing the second half of its revolution and the piston, carried by the momentum of the fly-wheel, is making its return or inward stroke, the valve being closed, however, a little before the stroke is completed, to leave an air-cushion in front of the piston, as is required in reciprocating engines running at a high speed. As the piston returns into the hot-air chamber *e*, it displaces fully all the rarefied air therein and forces it into the condensing-chamber *f*. So soon as the hot air passes into the cooler chamber *f* it begins to condense, by reason of contact with the walls thereof, and this condensation continues until the piston has completed its inward stroke and expelled the rarefied air from the hot-air chamber *e* into the condensing-chamber *f*, and the internal pressure within the cylinder is far below the atmospheric pressure. This condensation of the rarefied air is facilitated by causing it to flow from the communicating-ports *j* and the groove *i'*, through the narrow concentric space between the cylinder D and piston H, (see Fig. 2,) in direct contact with the entire inner periphery of this portion of the cylinder. At the moment the piston has completed its inward stroke, and its crank has passed the center, the valve O quickly opens, and the valve L being now closed the full atmospheric pressure is brought to bear upon the piston to force it outward and cause it to draw in a fresh supply of hot air from the burner R'. So soon as by the outward movement of the piston a pressure is created in the chamber *f*, the exhaust-valve F in the head of the cylinder D opens automatically, and allows the greatly-reduced volume of condensed air in said working or condensing chamber *f* to be freely discharged.

As the internal pressure obtained by condensation of the hot air in this engine is, under ordinary circumstances, about five pounds to the square inch, the working-pressure upon the piston when the hot-air valve O opens is about ten pounds to the square inch.

The engine is designed to be worked at a high speed. The air is drawn into the hot-air cylinder at its maximum temperature when most highly rarefied, and being forced out in its rarefied condition into the chamber of the condensing-cylinder is therein instantly cooled to create the partial vacuum by reason of which the motor is actuated. The hot-air cylinder becomes very hot, so that it will not materially condense the air admitted thereto, but, being separated by a non-conducting packing or otherwise from the condensing-cylinder, does not affect the effective operation of the latter.

I am aware that it is not new to construct an atmospheric engine in which the piston moves in a cylinder provided with an admission-port and valve for hot air at one end, and with a passage connecting the two ends of the

cylinder and having an outlet-port therein, said passage being controlled by a valve which opens the communication between the two ends of the cylinder and closes the outlet as the piston descends and opens the outlet and closes the communication when the piston ascends; but in this form of engine the hot air is condensed in the hot-air chamber, the chamber will soon become so hot as to prevent a condensation of the air, and the engine will cease running; or, if the chamber be cooled artificially, the hot air is unnecessarily robbed of its heat. By my invention this loss of heat is avoided. The temperature of the hot-air chamber remains almost constant. The temperature of the fresh supply of hot air is not lowered before it is brought into effective use, and when the air is fully rarefied and expanded it is condensed under the most favorable conditions in a separate chamber, which is kept comparatively cool.

I am also aware that an air-engine has been devised in which hot air from pipes encircling a furnace is admitted into a chamber against one end of a piston, and thence discharged through a valve-chest and communicating-passages into a chamber at the opposite end of the piston, the air being cooled and condensed in its passage from the one chamber to the other by suitable refrigerating appliances, and finally discharged from the upper chamber as the piston enters it by means of an automatic valve. In my invention the hot-air chamber is supplied directly from a burner with flame and products of combustion at the highest possible temperature, and the transfer of the hot air and gases from the hot-air to the condensing chamber is effected directly and governed positively, so that a far greater efficiency is obtained, and a more simple and powerful engine is produced than by the devices heretofore employed.

I claim as my invention—

1. The combination, with the hot-air and condensing chambers in an atmospheric engine, and with a reciprocating displacing-piston moving within the two chambers and serving as a movable partition between them, of a flame-inlet port in the outer end of the hot-air cham-

ber, a burner placed opposite said port, so that its flame and products of combustion may enter it directly; a communicating passage connecting the proximate ends of the two chambers, valves controlling, respectively, the flame-inlet port and the communicating-passage, and actuated automatically by the movement of the engine, so that the communicating-passage shall be opened when the inlet-port is closed and closed when the inlet-port is opened, and an exhaust-valve connected with the condensing-chamber and opening automatically to permit an outward discharge of air therefrom when the communicating-passage is closed, all substantially in the manner and for the purpose herein set forth. 65

2. The combination, with the hot-air chamber in an atmospheric engine and its flame-inlet port, of a lamp-burner placed opposite said port, a wick-tube and wick in said lamp, a pivoted toothed segment controlling the wick, a lever-arm fitted to the segment, and a governor upon the engine actuating said lever, whereby the variable movement of the governor operates to raise or lower the lamp-wick, and thereby increase or decrease the flame supplied to the hot-air chamber, all substantially in the manner and for the purpose herein set forth. 75

3. The combination, with the hot-air chamber in an atmospheric engine, a flame-inlet port in the outer end of said chamber, and a communicating-passage between the proximate ends of the hot-air and condensing chambers, of a slide-valve governing the flame-inlet port, a separate slide-valve governing the communicating-passage, a rotating shaft driven by the engine, and eccentrics upon said shaft connected, respectively, with the inlet-valve and the communicating-valve, whereby the inlet-port is positively closed as the communicating-passage is opened, and vice versa, substantially in 90 the manner and for the purpose herein set forth.

In testimony whereof I have signed my name to this specification in the presence of two subscribing witnesses.
